VARIABLE RADIO AERIAL

Adriano Cavalieri Ducati, Bologna, Italy

Application October 14, 1939, Serial No. 299,548
In Italy October 15, 1938

8 Claims. (Cl. 250—33)

This invention relates to aerials for radio communications of the variable length type for transmitting and receiving on different wave lengths and, more particularly, to aerials constituted by a column of liquid metal the height of which may be varied by pneumatic means.

The primary object of the invention is to provide a supporting tube for the liquid metal column, which is made up of a plurality of annular sections of alternatingly conducting and insulating material. With this arrangement, the metallic tubular sections serve for cooling the liquid metal and act as condenser elements connected in series, so that as the liquid conductor rises in the supporting tube coming into contact with the metallic parts of the tube, the operating conditions of the aerial are improved.

A further object of the invention is to provide an aerial comprising a fixed portion and an adjustable portion, the latter consisting of a liquid metal column supported by a tube formed by metallic annular sections alternating with annular sections of insulating material.

Further objects and advantages will appear from the following description in which reference is made to the accompanying drawing, wherein:

Figure 1 is an elevation of an aerial, of which the supporting tube is formed by a plurality of alternatingly insulating and metallic sections.

Figure 2 shows an aerial comprising a fixed portion and an adjustable portion.

Figures 3 and 4 show two types of joints for the aerials.

Referring to Figure 1, the tube enclosing the mercury column has an entirely metallic or insulating base portion 56 on which are alternately piled insulating and metallic tubular elements 57, 58, respectively, tightly sealed together. The tube is broken at an intermediate point in the drawing to show the tubular structure through which the liquid conductor forming the column 59 flows. The liquid is delivered from the sump 60 by means of the pressure fluid conveyed by pipe 61.

Figure 2 shows diagrammatically and by way of example one of the various manners of carrying out this invention. A tower antenna 62 has attached thereto the aerial 56, 57, 58 having at its lower end the sump 63, from which the pressure pipe 64 extends and delivers pressure for moving the column of the electric liquid conductor. Pressure is supplied by the source of pressure 65 and controlled by the pressure gauge

66, that may also directly indicate the length as adjusted.

The function of the device is in this case to correct the main aerial 62.

Figure 3 shows an example of a tight flanged joint 67 between the tubes 57 and 58 which, as said above, are insulating and metallic, respectively.

Figure 4 shows an example of a tight joint between the same tubes 57 and 58 employing set nuts 68 and 69, a bush 70 and resilient packings 71 and 72.

It will be understood that the tube joints and length and the types of materials employed may be varied at will. The insulating tubes may be made in the form of hose, such as rubber hose, or of material having a low dielectric loss, as porcelain, as the case may be.

It should further be noted that with regard to capacitive effects, the position of all these tubes may be compared with that of condenser elements connected in series, and this feature should be taken into account in determining the length of tubes constituting the aerial lead, and the height above the sump of this composite portion of the aerial lead.

It should further be understood that a metal other than mercury, which is liquid at room temperature, such as caesium, or an alloy, such as a sodium and potassium alloy, may be used, provided it has the necessary electric properties. When the last mentioned substances are employed the tube should be well closed at the top to prevent the access of moisture to the alloy.

It should finally be understood that the tubular metallic elements may be utilized for cooling the conducting liquid flowing therethrough, for which purpose these elements as well as the insulating elements shall be provided with ribs or fins for a more efficient cooling, when this is desired or useful.

What I claim is:

1. An aerial for radio communications comprising, a column of a metal in a liquid condition, and a supporting tube for said column constituted by tubular metallic sections alternating with tubular sections of insulating material.

2. An aerial for radio communications comprising, a tubular body constituted by tubular metallic sections alternating with tubular sections of insulating material, a sump into which said tubular body dips, a metal in a liquid condition in said sump and in said tubular body, and pneumatic means acting on the surface of the

liquid metal in said sump for adjusting the level of said liquid metal in said tubular body.

3. An aerial for radio communications comprising, a sump, a tubular body formed by a 5 metallic base portion dipping into said sump, tubular metallic sections alternating with tubular insulating sections on said base portions, a metal in a liquid condition in said sump and in said tubular body, and pneumatic means acting on 10 the surface of the liquid metal in said sump for adjusting the level of said liquid metal in said tubular body.

4. An aerial for radio communications comprising, a fixed aerial portion, an adjustable 15 aerial portion formed by a column of a metal in a liquid condition and by a supporting tube for said column made up by tubular metallic sections alternating with tubular sections of insulating material.

20 5. An aerial for radio communications comprising, a tower aerial, a sump at the upper end of said tower, an annular body constituted by

metallic tubular sections alternating with tubular sections of insulating material and dipping into 5 said sump, a metal in a liquid condition in said sump and in said tubular body, and pneumatic means acting on the surface of the liquid metal in said sump for adjusting the level of said liquid metal in said tubular body.

6. An aerial for radio communications comprising, a tubular member formed by tubular metallic sections alternating with tubular sections of insulating material, joints for sealing together 10 said tubular elements in a liquid-tight manner, a column of metal in a liquid condition in said tubular body, and means for varying the length of said column.

7. An aerial for radio communications as 15 claimed in claim 1, in which caesium is used as metal in a liquid condition.

8. An aerial for radio communications as 20 claimed in claim 1, in which a sodium-potassium alloy is used as a metal in a liquid condition.
